APPLICATION FILED MAR. 14, 1922.

Patented Sept. 12, 1922.

UNITED STATES PATENT OFFICE.

THOMAS MICHAEL SLOUGH, OF NEW ORLEANS, LOUISIANA.

PROCESS OF AND APPARATUS FOR THE MOLLIFICATION AND DISINTEGRATION OF AGGLUTINATE ELEMENTS.

Application filed March 14, 1922. Serial No. 543,805.

To all whom it may concern:

Be it known that I, THOMAS M. SLOUGH, a citizen of the United States, residing at New Orleans, in the parish of Orleans, in the State of Louisiana, have invented certain new and useful Improvements in the Process of and Apparatus for the Mollification and Disintegration of Agglutinate Elements, of which the following is a specification.

My invention consists in certain new and useful improvements in the process of and apparatus for the mollification and disintegration of agglutinate elements, and is designed more particularly for use in connection with the repairing and alteration of furniture and especially chairs, sofas, benches and similar articles of furniture having seats of cane, wicker, or other similar substances adhesively applied thereto. While my invention is more particularly intended to provide a new and useful method of removing chair bottoms, it will be apparent that it is applicable wherever two or more parts adhesively related are to be separated.

In applying cane seats to chairs it is a common practice to provide the frame of the chair bottom with a circumferential groove in which a spline bedded in glue is fixed for the purpose of holding the caned seat in place in the chair bottom. When it is necessary to remove the seat it is extremely difficult, by the methods at present in use, to remove this spline to release the seat. By my improved process, a fine jet of dry steam under pressure is applied to the spline, thus softening both the spline and the glue in which it is embedded. The end of the spline may then be raised from the groove and the spline peeled out, thus releasing the seat.

I have found the particular apparatus disclosed in the drawings filed herewith exceptionally well adapted for the purpose of practicing my improved process, as I have provided in a compact and simple device both the means for providing a jet of steam of the most efficacious character and also an improved nozzle adapted to both apply the steam to the parts and serve as a means of separating them when they have been properly softened by the action of the steam.

While I have indicated this proposed form of apparatus adapted for the purpose of

practicing my improved process, it is to be clearly understood that my process may be practiced by a wide variety of means, and it must be also understood that while I have set forth many of the uses of my process and apparatus, the scope of my invention is not to be limited thereby but is fully set forth in the claims appended hereto.

In the drawings:

Fig. 1 is a side elevation of my preferred form of apparatus.

Fig. 2 is a side elevation, partly in section, of a chair bottom, illustrating the use of the nozzle of my apparatus for removing a spline from the bottom.

In the drawings:

My improved apparatus is shown with a base frame A provided with two bracing platforms A¹ and A². Upon the platform A¹ there is suitably mounted a steam generator B of the ordinary type of copper-tube hot-water heaters. A pipe B¹ suitable for attachment to a source of gas supply is connected with the gas burner of the heater and provided with the usual stop-cock B². A pipe B³ is connected with the lower end of the coil of the heater B and extends within the frame A between the platforms A¹ and A². A pipe B⁴ is connected with the upper end of the coil of the heater B and is provided with the tap B⁵ through which water may be supplied to the heater B. Mounted upon the platform A² is the tank C to the top of which is connected the pipe B⁶. A gauge B⁷ and a relief valve B⁸ are interposed in the pipe B⁶ between the heater B and the tank C. From the bottom of the tank C a pipe C¹ connects with the pipe B³ and a drain-cock C² is provided in the union at their point of junction. A pipe C³ connects the pipe B⁴ with the tank C at a point mid-way of its height, and this pipe C³ is provided with a pet-cock C⁴ and a valve C⁵. From the top of the tank C extends the pipe C⁶ provided with a valve C⁷ and to this pipe C⁶ there is connected the flexible hose C⁸ provided upon its end with the improved nozzle D above referred to. This nozzle D is slightly curved and is provided with a small jet opening in its end.

From the foregoing description of the parts of my apparatus, its use will be obvious.

When a hose is attached to the tap B⁵ and

the tap B⁵ is opened, the coil in the heater B, pipes B⁴, B³, and G¹ and the tank C may be filled with water. If the pet-cock C⁴ is opened the water level in the tank C may be maintained level with the pipe C³. The water is then turned off; hose disconnected from tap B⁵; tap B⁵, pet-cock C⁴ and valve C⁵ are closed; gas is then admitted to the heater B and in the ordinary operation of the heater, the water in my apparatus is converted into steam, the heater supplying steam through the pipe B⁴ to the tank C. I have found that it is important that the steam be supplied to the nozzle at a pressure of 30 pounds, so I arrange the relief valve B⁷ to secure this result, the indicator B⁶ showing the pressure at all times. The steam is delivered through the pipe C⁶, by manipulating the valve C⁷, to the hose C⁸ and the nozzle D.

In Fig. 2 I have illustrated the relation of the chair bottom E with its groove E¹ and the spline F retaining the cane seat G. When the steam is properly delivered from the nozzle D it may be applied to the spline F thus softening the glue which holds the spline F in the groove, and also rendering the spline F pliable. Then the nozzle D can be used as a chisel to raise the end of the spline F from the groove E¹ and peel the spline F from the bottom E thus releasing the cane seat G.

Having described my invention, what I claim is:

1. The process of removing cane seats from chairs which consists in, first, subjecting the retaining spline to the mollifying action of steam and simultaneously subjecting the glue in which the spline is embedded to the liquefying action of the steam, and, second, peeling the spline from the chair by interposing a pointed tool having a passage for steam directing the steam to the very point of separation of the spline from the seat. 45

2. In an apparatus for mollifying and disintegrating agglutinate elements, the combination of a steam generator; a nozzle adapted to apply steam to the elements and shaped to apply disjunctive pressure between the elements at the point of discharge of the steam; and means adapted to supply the steam from the generator to the nozzle. 50

3. In an apparatus for removing splines from chairs, the combination of a steam generator; a nozzle adapted and shaped to apply steam under the spline and simultaneously apply disjunctive pressure between the spline and the chair; and means adapted to supply the steam from the generator to the nozzle. 55

In testimony whereof, I affix my signature.
THOMAS MICHAEL SLOUGH.
